UNITED STATES PATENT OFFICE.

THOMAS E. LANGSTON, OF FRANKLINTON, NORTH CAROLINA.

CLOTH CUTTER.

Application filed June 7, 1927. Serial No. 197,085.

This invention relates to cloth cutters of that type wherein a rotatable knife is mounted within a casing and driven by a motor.

5 The general object of the present invention is to provide a very simple, easily handled and easily operated construction of this character and one in which the knife is driven by means of a blast of air acting 10 upon the turbine or like air motor.

My invention is illustrated in the accompanying drawing, wherein:

Figure 1 is a side elevation of a cloth cutter constructed in accordance with my 15 invention;

Figure 2 is a section on the line 2—2 of Figure 1;

Figure 3 is a section on the line 3—3 of Figure 2.

20 Referring to this drawing, 10 designates a motor casing closed at one end by the end plate 11 and at the other end by the end plate 12. The motor casing is formed with flanges and the end plates are held to these 25 flanges by the bolts 13.

Disposed within the casing is a motor 14 having a shaft or trunnion 15, one end of this shaft or trunnion operating within a bearing 16 having means whereby it may be 30 lubricated, the other end of the shaft or trunnion operating in suitable bearings and being reduced, as at 17. The rotor consists of a barrel having the transversely extending 35 pockets 18 defined by the blades 19, these blades extending approximately tangential to the circle defined by the rotor. Opening into the casing or housing 10 is a tapered blast pipe 20 which discharges against the 40 blades and is provided with the controlling valve 21 of any suitable construction. This blast pipe 20 is adapted to be connected to any suitable source of air under compression. This blast pipe 20, it will be seen, constitutes a handle extending rearward from the 45 motor housing in off-set relation to the finger 25.

Extending from the housing 10 on one side thereof are the angular spacing members 22 or brackets which support the knife housing 23. The shaft or trunnion of the motor 17 passes through this housing and carries the nut 24. The housing is formed with the tangentially extending finger 25 and inward of this finger the housing is cut 50 away, as at 26, so as to expose the saw. This finger has a smooth upper surface from the

extremity of the finger nearly to the knife so that the finger may be inserted beneath several layers of cloth without injuring the cloth, the finger at its intersection with the 60 knife giving a point of support to the cloth on each side of the knife, and is adapted to be inserted beneath the cloth to be cut and then the cutter pushed along until the cloth is brought into contact with the rapidly 65 rotating knife or cutter 27. The housing 23 is provided with an air discharge port 28 through which the air passes after it has acted upon the motor.

The use of this device will be obvious 70 from what has gone before. It will be seen that this cutter is extremely simple, that it may be readily taken apart for repair or replacement, that it is light, portable and particularly effective. I do not wish to be 75 limited to the exact form of the rotor, though in actual practice I find this form to be of particular value. Any desired source of air may be used. The parts are preferably made of aluminum and the rotor will 80 be supported in ball bearings. The weight is about fourteen ounces and the motor will operate with about twenty-five pounds compression.

I claim:

1. A cloth cutter of the character described including a motor housing, a knife housing disposed laterally of and coaxially with the motor housing and having an elongated finger and being cut away at the base of this 90 finger, a blast pipe constituting a handle entering the housing tangentially in off-set relation to the finger and connected to a source of compressed air, a circular knife disposed within the knife housing, a motor within the 95 motor housing having a shaft extending into the knife housing and upon which the circular knife is mounted, the outer wall of the knife housing being cut away at its center to expose the end of the shaft, and a nut 100 engaging the end of the shaft and holding the knife in place upon the shaft, the motor including a rotor having a plurality of transversely extending pockets defined by blades, approximately tangential to a circle concentric to the axial center of the rotor, against which blades the blast of air is projected.

2. A cloth cutter of the character described including a motor housing, a circular knife housing disposed laterally of the motor housing and having an elongated finger, the knife housing being circular in general form and

having an outside and inside wall, the motor housing being cut away at its junction with the finger to expose the knife, a blast pipe constituting a handle and entering the handle tangentially and adapted to be connected to a source of compressed air, a circular knife disposed within the knife housing and operating between the outer and inner walls of the knife housing and finger, and a motor

within the motor housing having a shaft extending through the knife housing and upon which the knife is mounted, the motor including a rotor having a plurality of transversely extending pockets defined by transversely extending blades. 10
